UNITED STATES PATENT OFFICE.

THOMAS C. ROBINSON, OF BOSTON, ASSIGNOR TO E. BAKER WELCH, OF CAMBRIDGE, MASSACHUSETTS.

BASTING-MACHINE.

SPECIFICATION forming part of Letters Patent No. 378,905, dated March 6, 1888.

Application filed April 7, 1887. Serial No. 233,971. (No model.)

To all whom it may concern:

Be it known that I, THOMAS C. ROBINSON, of Boston, in the county of Suffolk and State of Massachusetts, have invented certain new and useful Improvements in Basting-Machines, of which the following is a specification.

My invention relates to sewing-machines, and particularly to that kind of such machines as are adapted to perform the work of basting or sewing with long stitches.

It is the object of my invention to construct a machine of the character mentioned which shall be simple in construction, cheap of manufacture, and certain and efficient in its operations, and in which the length of feed may be readily and easily adjusted.

The invention, which embraces a four-motion feed, is described and claimed hereinafter, reference being had to the accompanying drawings, and to the letters of reference marked thereon, forming a part of this specification, the same letters indicating the same parts wherever they occur.

Of the drawings, Figure 1 represents a bottom plan view of a machine embodying my improvements. Fig. 2 represents a front elevation, parts being represented in section on the line 2 2, Fig. 1. Fig. 3 represents a sectional rear elevation on the line 3 3, Fig. 1.

30 *a* represents the bed of the machine; *b*, the overhanging arm; *c*, the standard supporting the latter; *d*, the needle-shaft journaled in the overhanging arm; *e*, the needle-bar; *e'*, the needle; *f*, the presser-bar; *f'*, the presser-foot; *g*, the pitman, connected at its upper end with a crank device to the needle-shaft *d* and at its lower end to a crank or lever, *i'*, of short rock-shaft *i*, which latter device is in turn connected, through the medium of cranks or links and 40 pins of common construction, to the oscillating hook or shuttle-shaft *j*, for operating the shuttle *j'* in the race *j*.

The parts so far described do not differ materially in construction and function from a 45 sewing-machine of what is known as the "Singer" type, equipped for the performance of ordinary sewing, and therefore need not be more fully described herein.

k represents the feed-bar, provided with a 50 feed-dog, *k'*, adapted to operate in suitable

slots formed in the needle-plate *a'*, said feed-bar projecting at each end through slots formed in the depending flanges *a''* of the bed of the machine. The feed-bar has what is commonly known as a "four-motion" movement im- 55 parted to it—that is, an up and down and forward and backward motion, the former operation being accomplished by means of the rock-shafts *l* *m*, having bearings longitudinally of the machine in the depending flanges *a''* of the 60 bed thereof, shaft *l* being located near the front of the machine-bed and shaft *m* near the rear thereof. Shaft *l* is provided with a crank-arm, *l'*, extending toward the center of the bed and pivotally connected with a block, *l''*, 65 adapted to slide in a slot, *k''*, formed in the feed-bar *k*, and shaft *m* is provided with a crank-arm, *m'*, (similar to crank-arm *l'*,) which extends toward the center of the bed of the machine and is pivotally connected with 70 block *m''*, adapted to operate in slot *k'''* of feed-bar *k*, so that as said shafts *l* *m* are rocked in opposite directions and in unison a vertical or up-and-down motion will be im- 75 parted to the feed-bar when the latter is held from moving endwise, the slots *k''* *k'''* in the feed-bar permitting the blocks *l''* *m''* to operate without affecting the position of the bar longitudinally. Shafts *l* *m* are given a 80 rocking motion for the purposes before recited by means of eccentrics *n* *n'*, the former, on rock-shaft *i*, operating in the forked free end of an arm, *o*, connected at its other end to shaft *l*, and the latter, on shuttle-shaft *j*, operating in the forked free end of an arm, *o'*, connected at its 85 other end with shaft *m*. Feed-bar *k* is given a to-and-fro or horizontal movement by means of an arm, *p*, rigidly secured at its lower end to a rock-shaft, *q*, and pivoted at its upper end to one end of a link, *p'*, which at its opposite 90 end is in turn pivoted to the feed-bar, as clearly shown in Fig. 2.

An oscillating or rocking motion is imparted to rock-shaft *q* by means of a pitman, *r*, pivotally connected at its lower end with a short 95 arm, *q'*, rigidly secured to shaft *q*, said pitman being pivotally connected (as at *r'*) near its upper end with one end of a link, *s*, the other end of which is in like manner connected (as at *r''*) with the rearward end of a lever, *t*, piv- 100

oted at t' to standard c . The upper end of pitman r is forked, as shown at u , in which fork a cam, u' , is adapted to operate with the effect of imparting an oscillating and vertically-reciprocating motion to pitman r on its pivots $r' r'' t'$, as will be understood by an inspection of Fig. 3, and as is common in what is commonly known as the "Singer" machine. Lever t is provided with a handle, t' , and a friction device, v , operating against the sides of a slot, v' , of a bracket, v^2 , secured to standard c , so that said lever t may be rocked upon its pivot t' to bring pivot-points $t' r''$ in more or less nearly a vertical line with the axis of rotation of cam u' , and said lever be held by its friction device v in any position to which it may be moved. When pivot-points $t' r''$ are brought into nearly vertical line with the axis of rotation of cam u' , the vertically-reciprocating movements of pitman r will be short, and consequently but a short rocking motion will be imparted to shaft q ; but when said pivot-points are moved to a horizontal or nearly horizontal position with respect to each other the extent of movement of shaft q will be greater. Shaft q is mounted in brackets w , extending down some distance from the bed-plate a , so that arm p can be made quite long in order to impart a long throw, when desired, to feed-bar k through the medium of link p' .

By the means described a vertical movement is imparted to the feed-bar, which is given a reciprocating horizontal motion by means of rock-shaft q and its connections with said bar, the change in the throw of the latter having no effect whatever upon the former, and in this way by a slight raising and lowering of the feed-dog I am enabled to readily get a horizontal reciprocating movement of the latter of an inch or more.

In order to prevent the thread from being

drawn at a sharp angle around the sides or end of the slot in the presser-foot from the eye of the needle to the cloth when long stitches are being taken, I provide the presser-foot with a slot, x , as shown in Fig. 2, which obviates any undue tension on the thread and prevents a breaking of the latter or a puckering of the goods being operated upon.

Though I have been particular to describe the form and arrangement of the parts as here shown, it is obvious that these may be varied without departing from the nature or spirit of the invention.

Having thus described my invention, what I claim is—

1. In a basting-machine, the combination, with the feed-bar adapted to be moved vertically and horizontally, of two rock-shafts having a crank-connection each with the opposite ends of said bar to impart vertical motion thereto, and a third rock-shaft, also having a crank-connection with said bar to reciprocate the same horizontally, substantially as set forth.

2. In a basting-machine, the combination, with a slotted feed-bar, k , rock-shaft l , provided with crank-arm l' , block l'' , operating in one of the slots of said bar, rock-shaft m , provided with crank-arm m' , block m'' , operating in the other slot of said bar, rock-shaft q , crank-arm p , and link p' , substantially as set forth.

In testimony whereof I have signed my name to this specification, in the presence of two subscribing witnesses, this 1st day of April, A. D. 1887.

THOMAS C. ROBINSON.
